UNITED STATES PATENT OFFICE

147,798

DESIGN FOR A FLASHLIGHT

Miles J. Kelly, Waterbury, Conn., assignor to
Cresale Incorporated, Waterbury, Conn., a corporation of Connecticut

Application July 6, 1946, Serial No. 131,347

Term of patent 14 years

(Cl. D48—24)

To all whom it may concern:

Be it known that I, Miles J. Kelly, a citizen of the United States of America, residing in Waterbury, County of New Haven, and State of Connecticut, have invented a new, original, and ornamental Design for a Flashlight, of which the following is a specification, reference being had to the accompanying drawing, forming a part thereof.

Fig. 1 is a perspective view of the flashlight embodying my new design.

Fig. 2 is a front view of the same.

Fig. 3 is a top plan view of the same.

I claim:

The ornamental design for a flashlight as shown.

MILES J. KELLY.
